UNITED STATES PATENT OFFICE.

HENRY L. BLODGETT, OF CHICAGO, ILLINOIS.

SASH-CORD GUIDE.

SPECIFICATION forming part of Letters Patent No. 329,005, dated October 27, 1885.

Application filed September 28, 1883. Serial No. 107,606. (No model.)

To all whom it may concern:

Be it known that I, HENRY L. BLODGETT, of Chicago, in the county of Cook and State of Illinois, have invented certain new and useful Improvements in Sash-Cord Guides; and I do hereby declare that the following is a full, clear, and exact description thereof, reference being had to the accompanying drawings, and to the letters of reference marked thereon, 10 which form a part of this specification.

The primary object of this invention is to produce a construction in sash-cord pulleys in which the case may be provided with a face-plate or flange of circular form and of diameter small enough to enter a single sash-groove, while at the same time the pulley-shell (which of course cannot exceed in height the diameter of the face-plate) may afford the desired distance between the vertical parts of the cord. 15 By such a construction the pulley-shell may have the positive support of a face-plate, and the said face-plate may be let into the jamb by a bit-cut, which insures neatness and accuracy of fit with the least possible labor.

Another object of the invention is to provide 25 a construction of the pulley-wheel whereby the latter will be rendered nearly or quite noiseless in its operation.

To these ends the invention consists in the 30 matters hereinafter set forth, and pointed out in the claims.

In the drawings, Figure 1 is a perspective view of a sash-pulley containing certain features of my improvement. Fig. 2 is a vertical section transverse to the axis of the wheels of the sash-pulley shown in Fig. 1 applied to the window-jamb. Fig. 3 is a rear view of a sash-pulley constructed in accordance with my improvements. Fig. 4 is a side elevation of the 35 case pulley having the circular face-plate extended above the case, as shown in Fig. 3. Fig. 5 is a vertical section of the case through the axis of a pulley-wheel, showing devices having reference to the noiseless action of the pulley on its axis. Fig. 6 is a side view of one of the pulley-wheels having the last-mentioned improvement detached from the case. Fig. 7 is a perspective view of one of the small disks applied to opposite sides of the pulley around 40 its axis detached. Fig. 8 is an axial section of the pulley containing the last-mentioned

feature of construction, also detached from the case.

Referring to the drawings, A is a tubular portion of the case, and A' the circular face-plate cast therewith. Said face-plate is made circular in order that the recess made in the jamb to receive it may be cut with a center-bit with little trouble and perfect accuracy. Said face-plate is, moreover, small enough in 55 diameter to allow of its being inserted between the stops which form the walls of the same sash-groove. The tube A is therefore necessarily vertically shallow, and to give the desired distance between the vertical parts of the cord 60 two small pulleys, B B', are mounted in the shell, one behind the other, as shown. These pulleys are usually of equal diameter, and have their axes b in the same horizontal plane. The case A has its upper and lower edges, a a', 65 semi-cylindrical, whereby the aperture in the jamb to receive the tube may have its upper and lower ends cut by means of a bit of proper dimensions to enable the case to fit the aperture closely, the central portion of said aperture being taken out by a chisel in the usual manner. A special desirability of a close fit 70 of the tube in the jamb arises in the construction shown from the less leverage of the face-plate by reason of its being shortened in proportion to the lessened vertical diameter of the tube A, and the close fit of the tube in the jamb 75 will contribute to the security of the case or shell against the force of the weight suspended from its inner and overhanging pulley, B'. 80

The shell A may desirably be constructed of greater length than is usually required for a given medium or small size, and may have its hinder portion cut away at a², as shown, so that the inner pulley, B', may be set in different positions—i. e., either nearer to or farther from the pulley B, which is always set in proper position to allow the cord to clear the face of the window-jamb. By this construction the same shell A may be employed 90 for different thicknesses of jamb or for different forms of weight, or for varying conditions as to the weight-chamber in the window-frame.

In the use of the two relatively small pulleys B B' the face-plate, of proper width to be 95 inserted between the stops, or, in other words, of width not greater than the thickness of the

window-sash, may exceed the vertical depth of the shell A, and in this case I prefer to extend the face-plate above the shell A, in the manner indicated in Figs. 3 and 4, in order 5 that the upper projection may cover any space inadvertently left by inaccurately forming the aperture therefor in the jamb, and also for the purpose of forming a shoulder at this point calculated to better support the shell against 10 the downward strain of the weight from the rear pulley, B'. The screw-holes a^3 in the circular face-plate A' are located at the sides of the shell, as indicated in Fig. 3.

For the purpose of rendering the movement 15 of the pulley noiseless, said pulley is cast with a central recess, b^2 , around the axial aperture b' , and a centrally-apertured disk, B², Fig. 7, of Babbitt metal, rawhide, or other suitable material, and of proper size, is set in said recess 20 b^2 , as shown. Preferably the disk is forced into place, and, thus fastened to the pulley, will always turn with it and furnish an anti-friction, or, at least, a noiseless, bearing-surface when brought into contact with the side walls 25 of the shell. By making the disks B² of proper material and forcing them into the recesses b^2 , as described, so as to turn with the pulley, they form also a wearing-surface on the pivot-pin b calculated to support the pulley properly on 30 its axis as though the said pulley were constructed of a single piece of metal of the full width, presented in the present instance by the metal of the pulley proper and the thickness of the disks.

35 By reason of the greater rapidity and num-

ber of revolutions on the part of the smaller pulleys, B B', in the duplex construction herein shown, and resulting from the less diameter of said pulleys, the presence of the noiseless or anti-friction disks B² is especially advantageous in the form of pulley devices herein described. 40

It is obvious that in the construction set forth a minimum area of face-plate and pulley will be presented to the eye; that the strength and 45 other advantages of the projecting face-plate are retained, and that such pulley structure may be inserted or removed without cutting or removal of the parting-stop which divides the two grooves for the sash. 50

I claim as my invention—

1. The combination, with the shell and two cord-pulleys mounted therein, one behind the other, of the circular face-plate extending from the lower to a point above the upper edge of 55 the shell, said face-plate having diameter small enough to permit it to enter a single sash-groove, substantially as described.

2. In combination with a shell, a pulley recessed about its axis, and a plate or disk inserted in the recess of greater thickness than the depth of the recess, substantially as described. 60

In testimony that I claim the foregoing as my invention I affix my signature in presence of two witnesses.

HENRY L. BLODGETT.
